(57) CLAIM

The ornamental design for a support garment, as described and shown.

DESCRIPTION

FIG. 1 is a front-top perspective view of a support garment showing the new design;

FIG. 2 is a rear-bottom perspective view thereof;

FIG. 3 is a right side elevation view thereof;

FIG. 4 is a front elevation view thereof;

FIG. 5 is a left side elevation view thereof; and,

FIG. 6 is a rear elevation view thereof.

The portions shown in broken lines form no part of the claimed design.

1 Claim, 6 Drawing Sheets
